UNITED STATES PATENT OFFICE

1,979,207

CARTON FILLING MACHINE

Michael J. Milimoe, Chicago, Ill., assignor to F. B. Redington Company, Chicago, Ill., a corporation of Illinois

Application April 22, 1929, Serial No. 356,933

71 Claims. (Cl. 93—6)

The present invention relates to carton filling machines and particularly to that type of machine in which a folder or circular is inserted in the carton at the same time as the article.

The illustrated embodiment of my invention shows a machine which is adapted to insert tubes of tooth paste, shaving cream, and the like, into a carton, and to simultaneously insert a descriptive circular or folder in said carton by a certain novel means which will presently be described.

The present invention has for one of its objects the provision of a machine which is smooth in operation and which will insert the article and folder into the carton with a minimum amount of effort and much more quickly than in machines previously employed for such purposes.

Another object of this invention is the provision of means for insuring that one and only one carton will be delivered at predetermined intervals so as to prevent clogging of the machine.

Another object of this invention is to provide an improved feed chain for the articles which has a variable speed mechanism which causes the chain to move very slowly while the article is at the position where it is to be ejected from the feed chain into the carton, and to move rapidly after the article has been ejected and until the next article is in position to be ejected.

Another object of this invention is the provision of means for feeding the circulars or folders to a position between the article and the empty carton in which the article is to be placed.

Another and quite important object of this invention is the provision of a means which tends to partially fold the circular or folder prior to the time that the article comes into engagement therewith so as to insure that the circular or folder is carried into the carton by the article when it is engaged thereby and not deflected to one side or the other of the article as the article moves into the carton. By the use of this means, it is practically certain that each carton will receive a circular whereas, in some embodiments, it was found that if the article itself was used alone to carry the circular into the carton, quite a number of the circulars were deflected to one side or the other and did not enter the carton. The folding device may, however, be dispensed with.

The glue applying mechanism shown herein is described and claimed in my co-pending application Ser. No. 590,062.

In the drawings:—

Fig. 1 represents a front elevation of the machine which embodies my invention;

Fig. 2 is a plan view thereof;

Fig. 3 is an elevational view of the right hand end of the machine, as viewed in Fig. 1;

Figs. 4, 5, 6, 7, 8 and 9 are detail views of the

variable speed driving mechanism for the chain which carries the articles;

Fig. 10 is a front elevation of the means for transporting the cartons from the hopper to a position where the article is inserted, to a second position where the flaps are folded, and to a third position where glue is applied to the flaps; 65

Fig. 11 is a view similar to Fig. 10 but shows the parts in a slightly different position;

Fig. 12 is a plan view of the apparatus shown 70 in Fig. 10;

Fig. 13 is an isometric view of the means for stripping the cartons from the hopper and feeding them to a position where they may be opened and fed by means of the transporting device shown 75 in Figs. 10 to 12, inclusive;

Fig. 14 is a front elevation of the stripping mechanism shown in Fig. 13;

Fig. 15 is a view similar to Fig. 14 but showing the parts in a slightly different position; 80

Fig. 16 is a cross-section on the line 16—16 of Fig. 14;

Fig. 17 is an elevational view showing the hopper gate and the expander for opening the cartons; 85

Fig. 18 is a view similar to Fig. 17 but showing the parts in a slightly different position;

Figs. 19 and 20 illustrate the means used for adjusting the articles in the pockets of the feed chain so that they will be in proper position for insertion in the cartons; 90

Fig. 21 illustrates the manner in which the articles are placed in the cartons;

Fig. 22 is a view looking from the right in Fig. 20; 95

Fig. 23 is a view similar to Fig. 22 with the parts in a slightly different position;

Fig. 24 is an elevational view of the means for advancing the circulars to a position between a carton and an article located at their loading positions; 100

Fig. 25 is a plan view of the means shown in Fig. 24 and is drawn to a slightly larger scale;

Fig. 26 is a view taken substantially along the line 26—26 of Fig. 1 and shows the means for ejecting the article from the feed chain and the means for bending the circular prior to the time when the article engages said circular; 105

Fig. 27 is a view similar to Fig. 26 showing the article partially ejected from the feed chain and illustrating the manner in which the circular is bent before insertion in the carton; 110

Figs. 28 and 29 are views illustrating further details of the mechanism shown in Figs. 26 and 27;

Figs. 30 and 31 are views similar to Figs. 26 to 29, inclusive, showing a slightly modified form of the means for bending the circular; 115

Fig. 32 is a plan view of the means shown in Fig. 30;

120

Fig. 33 is a view similar to Figs. 30 and 31 but showing the parts in a slightly different position;

Fig. 34 is a view of the improved glue applying apparatus used in my invention;

Fig. 35 is a view similar to Fig. 34 with the parts in a slightly different position;

Fig. 36 is a plan view of the mechanism shown in Figs. 34 and 35 and also illustrates the manner 10-in which the flaps of the carton are folded prior to the gluing operation;

Figs. 37 to 39 inclusive are details of the folding means shown in Fig. 36.

Prior to my invention, it has been customary 15 in devices of this nature to use a feed chain having a plurality of pockets or buckets formed thereon for the purpose of supporting and carrying articles to a position where these articles may be inserted in a carton. These chains usually have been driven intermittently as by a Geneva movement, so that they were stopped while the article was being ejected from the pockets on the chains and this meant that when the chains were again put into motion to move the next article into 25 position, the chains would be given a sudden jerk which would cause the articles in the pockets to move around and out of the position intended so that when it was desired to eject the article from the chain, the article would not be in the position desired. Furthermore, chains which are 30 driven intermittently are less efficient in their operation and do not permit the articles to be positioned as rapidly as might be desired.

The present invention has eliminated most of 35 the difficulties arising from the use of a chain which is driven intermittently by providing a driving means for the chain which drives the chain continuously but at a speed which varies from a very slow speed to one which is considerably faster. To express it differently, it might be 40 said that the chain is moved so that it is moving very slowly while the article is near the position where it is to be ejected from the pocket, in which it rests, and moves rapidly after the article has 45 been ejected until the next article is near the position where it is to be ejected.

Other difficulties which were experienced with 50 prior devices have been overcome in the manner suggested in the objects of the invention and these will be more fully set forth as the description of the apparatus proceeds.

Referring now to the drawings and more particularly to Figs. 1 to 9, inclusive, the reference numeral 1 represents the frame of the machine 55 embodying my invention and 1' represents a supplemental frame member which rests on the frame member 1 and helps support the various parts of the mechanism, presently to be described. A plurality of shafts 2 and 3 having sprockets 8 and 8', respectively, rigid therewith, are adapted 60 to carry the chain 4 which has pockets or buckets 5 on the outer surface thereof for the reception of articles which are to be placed in cartons. The shafts 2 and 3 are rotatably mounted in brackets 9 and 6 respectively, the bracket 9 being 65 fastened to the supplemental frame member 1' and the bracket 6 being fastened to an extension 7 secured to one end of the frame 1.

The shaft 2 has a worm wheel 10 fastened rigidly thereto and adapted to rotate therewith, as 70 will be best seen in Fig. 4. A bracket 13 on the supplemental frame member 1' has a shaft 12 rotatably mounted therein and this shaft carries a worm 11 meshing with the worm wheel 10. A 75 chain 15 is trained over a sprocket 14 rigid with

the shaft 12 to drive the shaft which, in turn, drives the feed chain through the worm and worm wheel just described.

A bracket 20 on the main frame 1 carries the main drive shaft 19 which may be driven from any suitable source of power. A gear 18 is rigid with the shaft 19 and drives the gear 17 meshing therewith and rotatably mounted on a supplemental bracket 23 which is mounted on top of the bracket 20 and held in place by the bolts 24. The 8 downwardly extending ears 25 and 25' on the bracket 23 have stub shafts 17' and 16', respectively, rigid with respect thereto. The gear 17 is rotatably mounted on the stub shaft 17' and the sprocket 16, which has a disc 26 preferably 9 but not necessarily integral therewith, is mounted on the stub shaft 16'. The disc 26 has a roller 27 eccentrically mounted thereon and this roller is slidable between opposed guiding members 28 fastened in parallel relation to each other and 9 to a radius of the gear 17. The chain 15 is trained over the sprocket 16 as well as the sprocket 14.

As the gear 18 rotates, it drives the gear 17 and due to the pin and slot connection between the gear 17 and the disc 26 integral with the 10 sprocket 16, the latter are rotated about the stub shaft 16' and at a non-uniform speed. This non-uniform speed is transmitted by means of the chain 15 to the sprocket 14, shaft 12, worm 11, and worm wheel 10, to the chain 4 and is so timed 10 that the chain will be driven very slowly past the position where the article is to be ejected therefrom and move rapidly to position successive articles in position to be ejected.

It will be understood that the shaft 19 is rotating at a uniform speed and therefore the gears 17 and 18 also rotate at a uniform speed. However, it will be noted from an examination of Figs. 7, 8 and 9, that the uniform speed given to the gear 17 is transformed to a non-uniform 11 speed for the disc 26. Figs. 7, 8 and 9 represent three successive positions of the gears 17 and 18 and of the disc 26, the gear 17 rotating in the direction indicated by the arrows and each position of the gear 17 shows the gear rotated through 11 90° from its previous position. Therefore, in Fig. 8, the gear 17 has rotated thru 90° from the position shown in Fig. 7 but it will be noted that the roller 27 has rotated less than 90° about the stub shaft 16' and therefore must have rotated 11 at a speed slower than the speed of the gear 17 while traveling from the position shown in Fig. 7 to that shown in Fig. 8. However, when the gear is moved from the position shown in Fig. 8 to the position shown in Fig. 9, the roller 27 moves more 11 than 90° about the stub shaft 16' thereby rotating the disc 26 at a speed which is greater than the speed of rotation of the gear 17. As the gear 17 rotates from the position shown in Fig. 9 to a position 90° farther on in the same direction, the 11 roller 27 will move approximately the same amount as it does when moving from the position shown in Fig. 7 to the position shown in Fig. 8 and similarly in the next 90° of rotation of the gear 17, the roller 27 moves through the same 1 angle as it does when moving from the position shown in Fig. 8 to that shown in Fig. 9.

Since the movements of the disc 26 are transmitted through the sprocket 16 and the chain 15 to the feed chain 4, it will be seen that the 1 latter will receive a movement which is alternately fast and slow. The various proportions of the disc 26 and gear 17 may be varied and the roller 27 may be given more or less eccentricity 1 than that illustrated, or the stub shafts 17' and 1

16' may be offset more or less than that illustrated to vary the ratio between the slow and fast speeds of the chain 4, as desired, it being understood that the same principles of operation apply even though the proportions may be changed as stated.

Referring now to Figs. 10, 11 and 12, a means is provided for transferring the cartons 30 from a position within the hopper 29 to the position where they are to receive the article. The hopper 29 has a front wall 31 and a rear wall 31', the latter having a longitudinal slot therein for permitting the operator to place the cartons in the hopper. The hopper also has a wall 32 on one side thereof connecting the walls 31 and 31' and a hinged plate 33 is pivoted to a pin 34 fastened to the rear wall 31' and at one side thereof so that it can be swung against the ends of the cartons in the hopper to align the cartons.

The cartons are removed from the bottom of the hopper by means of a stripping device which is later to be described, and, to insure that the cartons will settle to the bottom of the hopper, the hopper is provided with a combined gate and agitating device which comprises a lever 36 shown more in detail in Figs. 17 and 18, and this lever is pivoted at 37 and carries a gate 40 which passes through an opening 35 in the front wall 31 of the hopper and is adapted to engage the edges of the cartons within the hopper.

A screw 38 is screw-threaded into the bracket 38' fastened to the hopper and passes freely through an opening in the upper end of the lever 36. A spring 39 surrounds the screw 38 and yieldingly urges the lever 36 against the head of said screw, which head limits the movement of the lever in that direction. For moving the lever against the action of the spring 39, said lever is provided with an extension 41 which has a cam surface 42 adapted to be engaged by a roller 43 rotatably mounted on a reciprocating lever 44. The lever 44 is reciprocated by means of a cam actuated lever 45 co-operating with the cam 45'. Each movement of the lever 44 to the left moves the lever 36 clockwise and each movement of said lever 44 to the right releases the lever 36 so that it is free to rotate counter-clockwise and thus urges the gate 40 in a downward direction. The weight of the cartons in the hopper permits the gate 40 to ride over the edges of said cartons on its upward movement since there is not enough friction between the gate 40 and the edges of the cartons to carry the cartons along with the gate in its upward movement. However, as the gate 40 begins its downward movement, the friction between the gate and the cartons, supplemented by the weight of the cartons, produces a force sufficient to insure that the cartons always move toward the bottom of the hopper and that there is always a carton ready to be stripped from the bottom of the stack of cartons in the hopper. The gate 40 also serves as a gauge to insure that only one carton at a time can be carried out of the hopper. For this purpose, the lower edge of the member 40 while in the position shown in Fig. 17, is adjusted by means of the screw 38 to a distance less than the thickness of two cartons and more than the thickness of one carton, away from the support 76 on which the bottom carton rests so that said gate will prevent the carton second from the bottom from coming out of the hopper with the bottom carton. It will be understood that when the bottom carton is being stripped from the stack of cartons, the gate is in the position shown in Fig. 17

and not that shown in Fig. 18 where it is shown slightly raised.

The lever 44 receives its motion from a cam actuated lever 45, later to be described. The shaft 46 rigidly mounted in a bearing 47 has guides 48 slidably thereon and these guides support a member 49 which has a pivotal connection at 50 with the lever 44 and guides the movement of said lever. An expander 51 is also mounted on the member 49 and this expander is adapted to enter the carton as said carton is moved into its first position in front of the hopper 29, as will be best shown in Fig. 11, which shows the expander within the partially opened carton.

To fully open the carton and to then move the carton to successive positions in advance of the hopper 29, I provide a transporter designated as a whole by the numeral 52. The transporter is pivotally supported at 55 and 56 on the levers 53 and 54, respectively, which, in turn, are pivotally connected to and supported by the bell crank levers 60 and 61, respectively, as will be best seen in Figs. 10 and 11. The bell crank levers 60 and 61 are pivoted at 59 and 62, respectively. The bell crank lever 60 has a roller 64 rotatably mounted on a projection integral with one arm thereof and this engages a cam groove 69 in the cam 67, rotation of which imparts a rocking motion to the bell crank lever and this motion is transmitted by means of the connecting link 65 to the other bell crank lever 61. The bell crank levers 60 and 61 oscillate about their pivots in unison and cause the levers 53 and 54 to alternately raise and lower said transporter to the positions shown in Figs. 10 and 11. Means is also provided for moving the transporter longitudinally at the same time as it is given the up and down movement just described. This means comprises the lever 58 pivoted on the same pivot 59 as is the bell crank lever 60 and 115 said lever 58 has a roller 63 engaging a cam groove 68 in the cam 66 and as the lever is oscillated about its pivot, this motion is transmitted to the transporter through the connecting links 57 and 53. The connections just described 120 give to the transporter 52 a combined motion which moves the transporter to the right from the position shown in Fig. 10 and then downwardly and to the left, and, finally, substantially vertically to its original position. During the 125 movement of the transporter to the right, the cartons 30 are carried along therewith and simultaneously a carton is stripped from the bottom of the stack of cartons in the hopper 29. This stripping mechanism, best illustrated in Figs. 13, 14, 130 15, and 16, will now be described in detail.

In Figs. 14 and 15 are shown two positions of the stripping mechanism as seen from the same side of the transporter as seen in Figs. 10 and 12. The position shown in Fig. 14 illustrates the position of the mechanism just before stripping a carton from the stack of cartons in the hopper, and Fig. 15 shows the position of the mechanism just after it has begun its movement towards the right and started to strip a carton from the bottom of the stack of cartons in the hopper. The transporter comprises two parallel members 52' and on the extreme left hand portion of each of said members is rigidly mounted a bearing 72 and each of these bearings has a member 70 pivoted thereto as at 71 and carries a stripper bar 74 having an outwardly and upwardly extending projection 75 on the right hand portion thereof and this projection is intended to engage the lowermost of the cartons in the stack 140 145 150

and carry it out of the hopper between the front wall 31 thereof and the supporting bar 76 on which it is adapted to slide. Each member 70 has a recess therein to receive one end of a spring 73, the other end thereof being received in a similar recess in the member 52'. This spring normally urges the member 70 upwardly away from the member 52' but the upper movement thereof is limited by a stop 79 engaging a projection 80 on the member 52'.

A pin 81 in each of the members 70 is adapted to engage and be actuated by cams 82 and 84 fastened to the member 76 and in a manner later to be described. The cartons in the hopper are adapted to rest upon the projections 78 and 78' adjacent recessed portions 77 and 77' in the members 76 and 76', respectively. This insures that the edges of the lowermost carton always lie in the same plane for if the cartons were slightly warped and the member 76 did not have the cut-away portions 77 and 77', the edges of the lowermost carton would not always be in the same plane due to the fact that the warped portion would have a tendency to make the carton lie irregularly on the surface of the member 76. It will be readily understood that if the edges did not always lie in the same plane, the projection 75, which is adjusted so that its upper edge lies at a distance above the surface of the member 76 which is not greater than the thickness of a carton stacked in the hopper, will either engage more than one carton or not engage any cartons at all depending upon whether the edges of the lowermost carton are below or above that normally intended. If the carton is warped downwardly, the bellied portion thereon extends downwardly into the cut-away portions 77 and 77' and the position of the edges thereof is not materially affected. If, however, the carton has its warped portion extending upwardly, it would not materially affect the operation of the stripper. One end of the member 76 is fastened by means of the bolt 86 to a projection 83 integral with the rear wall 31' of the hopper. The member 85 is fastened to the member 76 and has the cam member 84 fastened thereto.

Starting with the parts in the position shown in Fig. 14, it will be noted that the pin 81 is in engagement with the cam 84 and therefore the member 70 is held downwardly against the action of the spring 73 so as to position the upper edge of the projection 75 so that it is not above the upper edge of the lowermost carton in the hopper. As the member 52' moves toward the right, carrying with it the member 70, the projection 75 on the stripper 74 engages the edge of the lowermost carton and carries it forward as shown in Fig. 15, the front edge of the carton passing through the opening between members 31 and 76 into a position in front of the hopper 29. Soon after the member 52' moves to the right, the pin 81 is free of the cam 84 so that in case the carton is warped upwardly, the action of the spring 73 will yieldingly urge the stripper 74 upwardly so that it will not come out of engagement with the edge of the carton. The surface 70' of the member 70 helps to support the carton as it is being carried forward and to guide it into engagement with the stripper 74.

Again referring to Figs. 10 to 12, inclusive, it will be noted that the transporter, as shown in Fig. 11, is in its lowermost position and the carton 30, just to the right of the front wall 31 of the hopper, has been partially opened by the expander 51 and that the member 70 is consider-

ably below the bottom of the hopper and is in a position where it is to be raised vertically along with the transporter into the position shown in Fig. 14 or Fig. 10. As the transporter moves from the position shown in Fig. 11 to that shown in Fig. 10, the projection 87 engages the left hand portion of the carton and while one side of the carton is held down against the member 76 by means of the expander 51, the projection 87 engages the side shown directly above it in Fig. 11 and opens the carton still further until it is in the fully opened position, shown in Fig. 10. While in this fully opened position, the upper side of the carton is engaged by the friction member 92 which co-operates with the member 76 to hold the carton in its fully opened position. The shorter projection 88 on the transporter assists the projection 87 by keeping the carton from sliding to the right until the carton is fully opened at which time it is carried bodily to the right by the movement of the transporter, previously described. After the transporter has moved to the right a distance which will position each carton in its next successive position, said transporter drops downwardly and then moves backwardly, in the manner previously set forth in detail, so that it is in the position shown in Fig. 11 and can again carry out the cycle of operations just described. The carton which was previously moved forward between the projections 87 and 88 will be moved forward by the projections 89 and 90 during the next cycle of operation, and the similar projections 91 are used to advance the carton to the successive positions shown as the transporter passes through each cycle of operation until it is no longer necessary to keep the cartons separated as they are at the left in Figs. 10 and 11. Thereafter, the last projection 91 to the right pushes all of the cartons arranged to the right thereof until they are removed from between the members 92 and 76 by hand or by any suitable mechanism, or are carried to the end of the supports 76 and 76' and deposited in a suitable receptacle.

While the carton is in one of the successive positions shown in Figs. 10 and 11, it is opposite the unloading position for the articles in the feed chain 4 and the transporter is so timed that the carton is stationary while the article is being inserted therein. However, it is possible with this device to have the carton move slowly along with the slow feed of the chain so that the carton can be filled while it is still in motion. For instance, I might use a continuously moving carrier as in my Patent No. 1,486,598, granted March 11, 1924. A chain similar to the chain 4 might be used to keep the cartons opposite the article pockets in the chain 4.

Means are provided for positioning a folder or circular C between the carton and the article prior to inserting the article in the carton. This comprises the hopper B having a member B' pivoted thereto for the purpose of engaging one edge of the circulars adapted to be placed therein, as best seen in Fig. 2, and a suitable mechanism 94, of well known design, is used to remove the circulars from said hopper and place them in a position such as that shown in Figs. 24 and 25. In these figures, C represents the initial position of the circular and C¹, C², C³, and C⁴ represent successive positions thereof. While in the present instance, the device illustrated shows means for folding the circulars and feeding the same to a position between the carton and the article, it will be understood that these circulars need not be folded and that any other desired

mechanism may be used to position the circulars between the carton and the article.

While the circulars are at the position C, they are not folded and are positioned just in front 5 of the knife 95, which has a straight vertical edge, as best illustrated in Fig. 24. The knife 95 moves to the right against the circular C and carries it between the opposed guides 96 and 97 supported on the brackets 98' and 97', respectively, the 10 rounded forward edges of the guides assisting the knife in folding the circular in the manner illustrated in the successive positions C¹, C², C³ and C⁴. The knife is reciprocated by means of a cam actuated lever 100 connected to the bracket 98 15 rigid with the knife 95 by means of the lever 99. The bracket 98 has a portion thereof clamped around the rod 101 slidable in suitable bearings in the frame. This rod 101 also has a pair of brackets 102 and 103 clamped thereto and these 20 carry the member 104 which has projecting finger-like extensions 105, 106 and 107, integral therewith. As the knife moves the circular from the position C to C¹, the finger 105 moves against the circular already at C¹ and carries it to the 25 position C². Similarly, projections 106 and 107 carry the circulars from the positions C² and C³ to the positions C³ and C⁴, respectively, the latter position being between the carton and the article. As the knife 95 moves to the left, the member 30 104 moves therewith and to prevent the circulars from being drawn back therewith, the guide 97 is provided with a plurality of projections 108 and 108'. These engage at least one of the folded edges of the circular but are spaced sufficiently 35 from the member 97 so as to permit the finger-like extensions 105, 106 and 107 to move the circular therebetween. The circulars are of course able to yield a sufficient amount in order to do this.

40 The projection 108 is arranged to yield so that it will permit the knife to go past as it carries the circular to the position C¹. To permit this yielding movement, the projection 108 is arranged in a bracket integral therewith and having openings 45 therein adapted to surround the pins 110 and 111 which guide it in a parallel direction toward and away from the member 96. The spring 109 normally urges the projection 108 towards the guide 96 and the knife 95 moves the projection 50 away from the member 96 due to its engagement therewith as it moves the circular to the position C¹. As the knife is withdrawn, the projection 108 moves into the position shown in Fig. 25 to prevent the circular from being carried back 55 with the knife.

60 The guide member 97 has an opening 112 therethrough at the extreme right hand portion, as shown in Figs. 24 and 25. This opening is located directly opposite the opening in the carton 30 and between the carton and the circular located at C⁴. Referring now to Figs. 26, 27, 28 and 29, a means is shown for causing the article A to move from the pocket 5 into the carton 30 and for carrying the circular along therewith. 65 The cartons 30, in addition to being supported by the member 76, are supported on the members 76'. This forms a more rigid support for the cartons which is necessary particularly when the article is being inserted therein. In Fig. 26, the circular C⁴ is shown in position and if the article were moved forward against the circular and through the opening 112 in the member 96, the circular would be folded over the end of the article and be carried into the carton therewith, 70 but it has been found in ordinary practice that,

quite often, the circular will not bend as desired but will slip off to one side as the article is moved into the carton and if this is not noticed, the wrapped article will be sent out without a circular accompanying it. Therefore, a special means is provided to insure that the circular will fold along the proper line so that when it is engaged by the article, it will be carried along therewith. This means comprises a circular folding device, or breaker, as it will hereinafter be termed, 80 115 pivoted at 117 to an extension 114 of the bracket 113 mounted on the auxiliary frame 1'. A spring 116 surrounds the pivot 117 and is so coiled as to urge the breaker 115 in a clockwise direction about the pivot. The breaker 115 has a portion thereof at 115' bent at an angle to the main or body portion thereof and this acts as a limiting stop for the breaker in its clockwise rotation as it is so designed as to engage the bottom of the groove 122 in the guiding member 121, 85 as best illustrated in Fig. 26.

90 As the article A is ejected from the pocket 5, the head thereof strikes against the member 115 and swings the member 115 about its pivot as in the manner illustrated in Fig. 27. The portion 115' engages the circular prior to the time that the circular is engaged by the article and since this portion 115' is of substantial width the tendency of the circular will be to fold over the edge thereof and not be deflected to one side or the other as is sometimes the case where the circular is engaged only by the head of the article and depends upon such engagement for folding the circular over the article.

95 It can readily be seen that, as the article moves farther to the right and into the carton, the breaker 115 will be swung upwardly out of the way of the article and that the head of the article will engage the circular substantially along the line where it was folded by the member 115' and 100 carry the circular into the carton. The opening 112 has beveled upper and lower edges, as best seen in Figs. 30 and 31 and these aid the breaker 115 in folding the circular.

105 Means are also provided for automatically 120 ejecting the article from the pocket 5 and causing it to move against the breaker and circular and into the carton 30. This means comprises an ejector 119 supported on the end of a lever 120 and the lever 120 is pivoted at 123 to a block 126 125 which, in turn, is pivoted to the bracket 125 at 124. This bracket 125 receives a motion toward and away from the feed chain 4 by mechanism later to be described. This movement carries the ejector 119 against the end of the article in 130 the pocket 5 and moves the article into the carton in the manner already described.

135 Figs. 26 and 27 illustrate, respectively, the positions of the ejector 119 just prior to ejecting the article and just after such ejection has been begun, and Figs. 28 and 29 illustrate the positions of the ejector 119 as it is moved away from the carton and the pocket into a position where it will be in readiness to eject the next article in the next pocket.

140 To raise the ejector 119, there is provided a lever 127 having a roller 128 engaging the underside of the lever 120 and rollers 128' on either side of the lever 120 for guiding said lever during its reciprocating movement. A guide member 129 145 engages the upper side of the lever 120 so that the lever will not raise up at an inopportune time. The lever 127 is cam actuated so as to be raised as the ejector 119 begins its return movement. This insures that the ejector will clear the chain which 150

is then moving at a rather rapid rate to position the next article in a position to be ejected. It will be noted that the chain 4 has supporting members for the pockets thereof comprising a 5 pair of upstanding guides 4' in order to always keep the pockets at the proper height.

The upper end of the lever 127 is pivotally connected at 130 to a link 131 and this link, in turn, is pivoted to one of the guides 4'. The specific 10 means for actuating the lever 127 is best illustrated in Figs. 1 and 3. These views show the lever 127 pivoted to one arm 151 of a bell crank lever, the other arm 152 thereof being adapted to engage the cam groove in the cam 133 rigidly 15 mounted upon the shaft 66'. The bell crank lever is pivoted to a bracket 153 mounted on the auxiliary frame member 1'. The arm 152 and link 131 give a substantially parallel rotation to the lever 127 so that the lever is not canted.

20 The bracket 125 is rigidly mounted on a rod 134 (see Fig. 3) which is guided in suitable bearings in the frame and has a member 135 rigidly fastened to one end thereof. This member 135 engages a guide 136 and is guided thereby, thus 25 preventing rotation of the shaft 134 about its axis. A cam actuated lever 138 having a roller 139 engaging a cam groove in the cam 140 has a connecting link 137 pivotally connected thereto and to the member 135 so that the oscillations of 30 the lever 138 impart a reciprocating movement to the rod 134 through the link 137 and the member 135. This gives a reciprocating movement to the member 125 as previously described. The lever 138 is pivoted to the shaft 22.

35 The shaft 66' carrying the cams 66, 67, 107 and 133 is rotated by means of the gears 141 and 142 connected, respectively, to the shaft 66' and the main drive shaft 19.

In Figs. 30 to 33, inclusive, I show a modified 40 arrangement for moving the breaker against the circular and for thereafter retracting the breaker. It has been found that when the breaker is constructed as shown in Figs. 26 to 29, inclusive, the breaker does not always return to its normal position 45 in a vertical plane, in view of the fact that the spring which is used to return the breaker often gets gummed up. The modification shown in Figs. 30 to 33, inclusive, avoids the possibility that the breaker 115 might not return 50 to a vertical position or at least to a position which will not interfere with the positioning of the circular in the position C⁴ by providing a more positive means for returning the breaker 115 as the ejector is being withdrawn.

55 This means comprises a slidable member 144 which is pivoted at 143 to the breaker 115 and has the other end thereof slidably mounted between the opposed pins 145 fastened in the bracket 125. These pins 145 have a plate 146 60 with openings therein which slide over the ends of the pins to permit the plate to frictionally engage one side of the member 114 and springs 147 surrounding the pins 145 urge the plate 146 against the member 144, thereby offering resistance to the sliding of the member 144 between the opposed pins 145. The member 144 is provided with a cut-away portion 148 and is provided also with stops 149 and 150 for purposes presently to be described.

70 With the parts in the position shown in Fig. 30, the ejector 119 starts its movement towards the right to eject the article from the pocket 5. There is sufficient friction between the plate 146 and member 144 to cause this member to move 75 forwardly along with the ejector 119 until the

stop 149 arrests the motion of the member 144 by coming into engagement with the bracket 129 upon which the rollers 128 and 128' are mounted. Thereafter, the member 144 slides between the plate 146 and the bracket against the force 80 of friction. However, after the member 144 moves between the plate 146 and bracket 125, a sufficient amount, the cut-away portion 148 thereof comes between the plate 146 and bracket 125 and permits the member 144 to move freely 85 therebetween. This cut-away portion permits of this movement so that as soon as the breaker has accomplished its purpose, it will fall of its own weight against the article during the last part of its movement into the carton and also 90 against the ejector so that as soon as the ejector begins its rearward movement, the weight of the breaker 115 and member 144 tend to move the breaker about its pivot in a clockwise direction and during the last part of the rearward movement of the ejector, the friction plate 146 again 95 acts on the end of the member 144 to draw the same into the position illustrated in Fig. 30 and to thereby draw the breaker into a vertical plane, the block 150 limiting the movement of the 100 breaker 115 in a clockwise direction. In addition to the more positive actuation of the breaker 115, the means just described operates the breaker in such a way that it is not necessary for the article itself to do any substantial amount of work in 105 connection with folding the circular and, therefore, renders the machine more efficient in its operation.

As previously described, the chain 4 moves very slowly while in a position which is substantially 110 opposite to the opening in the carton, and, in Fig. 32, one of the pockets 5 of the chain is shown in the position which it occupies just before the ejector engages the pocket to remove the article 115 therefrom. It will be noted that the opening in the pocket is not symmetrical with a line through the center of the carton but is in a position a little to one side of such a line. The pocket is adapted to move in the direction illustrated by the arrow and during the time that the ejector 120 is ejecting the article from the pocket, it moves from the position illustrated until the inner edge 5' is in alignment with the inner edge 121' of the guide member 121. Since the ejector is of substantially the same width as the pocket, it 125 is necessary that the ejector move with the pocket in the direction of the arrow in order that it can also move from left to right to eject the article and for this reason, the lever 120 has a portion 120' forming a cam surface which co-operates 130 with the roller 128' adjacent thereto to pivot the lever 120 about the pivot 123 just the right amount to cause the ejector to move with the pocket 5 in the direction of the arrow. An auxiliary guide member 122' assists the entry of 135 the article into the carton.

Articles such as tooth paste tubes, have a tendency to roll in the pockets especially when the chain is given an irregular movement so that even though the tubes are placed in the pockets as desired, the same may move to other positions before it is desired to eject the tube from the pocket. A great many manufacturers desire to have the tube A inserted in a carton 30, such as illustrated in Fig. 21, the width of which is less 145 than the width of the clip A' on the end of the tube so that it is necessary to insert a tube with the clip arranged in the diagonal manner shown in Fig. 21. Therefore, if the tube is not in this position at the time it is to be ejected from the 150

ocket, the same will not enter the carton or else will cause damage to the carton. Therefore, it has been found desirable to provide a means which will insure that the articles are in the desired position at the time when they are to be ejected. This means comprises a plate 154 and brackets 155 and 171 fastened to the auxiliary frame 1' and these in turn carry suitable aligning means. The member 155 has the arm 156 pivoted thereto at 157 and the pins 158 and 159 provide stops which limit the movement of the arm 156 in clockwise and counter-clockwise directions, respectively. Assuming that the chain is moving in the direction of the arrow shown in Fig. 19, it will be noted that the arm 156 is just about to engage the article A located in the second pocket of the chain, counting from the left. It will be noted that both of the articles in the first two pockets are not in the desired position but as the chain carries the articles under the arm 156, said arm rotates them into a position shown by the article in the third pocket. This arm is ordinarily heavy enough to cause the article to rotate but if desired may be provided with a spring to rotate it clockwise.

Since the article in the third pocket is not in as firm engagement with the edges of the pocket as could be desired, a second means is provided for rotating the article still further. This means comprises a bracket 160 mounted on the plate 154 and this bracket carries a pin 161 which passes through an opening in the angle bracket 162. A spring 163 surrounds the pin 161 and yielding urges the plate 162 downwardly. The plate 162 has an angular extension 164 overlying the upper surface of the chain, as best illustrated in Fig. 22, and this tends to firmly seat the articles in the pockets so that the articles will occupy the position shown in the fourth pocket of Fig. 19.

Sometimes when the tubes are placed in the pockets, the ends of the clip A' at the bottom thereof will rest on the opposite edges of the pocket, in a manner which is best illustrated with reference to the third pocket shown in Fig. 20. With the tube in this position, neither the arm 156 or the angular extension 164 will be able to straighten the tube in the pocket until the ends of the clip are removed from the opposite edges of the pocket. For this purpose, I have provided a kicker 165 pivoted at 167 to an arm 168. This arm in turn is pivoted at 170 to the bracket 171. A spring 174 having its opposite ends fastened to the kicker 165 and arm 168 tends to yieldingly urge these members toward each other about the pivot 167. This keeps the kicker 165 firmly in engagement with the plate 154 at all times and this plate 154 forms a guiding means to guide the kicker in its movement. Rigidly fastened to the bracket 125 is a follower 172 carrying a roller 173 engageable with the cam surface 169 of the arm 168.

The stop 175 on the arm 168 is adapted to engage a stop 176 to limit the rotation of the arm 168 about its pivot 170. The bracket 171 has a guide bearing therein for guiding the rod 134 during its reciprocation. The operation of this mechanism is as follows:—

When the tube and the kicker are in the positions shown in Fig. 23, the follower is at its extreme left hand position and as it moves to the right, it engages the cam surface 169 and this movement tends to rotate the arm 168 clockwise and to move the kicker 165 from the position shown in Fig. 23 to that shown in Fig. 22, the

edge 166 sliding along the plate 177 until it reaches the edge of the plate and thereafter the edge 166' slides along the edge of the plate, as best illustrated in Fig. 22. During this movement, the upper end of the kicker engages the clip on the tube in the adjacent pocket if the same is in a position such as that shown in Fig. 23 or in the third pocket of Fig. 20 and raises the tubes sufficiently so that the edges of the clip are free from the edges of the pocket and the tube drops into the position shown in the fourth pocket of Fig. 20 and is thereafter engaged by the arm 156 and the angular extension 164 to straighten the tube in the pocket.

The chain 178 driven from the shaft 66' is adapted to drive the shafts 179 and 180 to actuate the feeding mechanism 94 for the circulars C.

The beveled portion 5' of the pocket 5 permits the adjacent edge of the clip to drop into the pocket when the clip is kicked by the kicker 165.

After the article has been placed in the carton, the flaps of the carton are ready to be glued so as to seal the carton and a novel means for doing this has been provided in the embodiment shown. It will be understood, of course, that were it desired to use a carton with only a tucked flap, the gluing mechanism may be dispensed with and suitable tucking mechanism may be substituted therefor in a well-known manner.

While the carton is at the position where the article has been inserted, a projection or folding device 200 engages the adjacent flap and folds that flap inwardly to a position substantially at right angles to the longitudinal dimension of the carton, and the folding device 201, actuated by a cam, folds the opposite flap over the first mentioned flap. Thereafter, the cam 204 having the inclined faces 204' engages and folds the upper flap, as seen in Fig. 34, to the position which overlies the first two flaps mentioned. Similarly, the lowermost flap 212 is folded downwardly by a folding device 210 so as to expose the surface of the flap which is later to be folded over into engagement with the third mentioned flap, with a layer of glue therebetween to seal said flaps together. Folding devices 202, 203 and 209 corresponding with the folding devices 201, 204 and 210 are adapted to fold the flaps in a similar manner at the other end of the carton, the last of the flaps 211 being folded into a position similar to the flap 212. A folding device, not shown, located beneath the member 205, and similar in its action to the folding device 200, co-operates with the folding device 202 to fold the opposed flaps at the adjacent end of the carton.

Members 205 and 206 carry the folding devices 200, 203 and 204 and also the member 92. A member 206' is fastened to the member 92 and is pivoted at 208. The member 205 is pivoted at 207 and by raising either the member 205 or 206', the framework composed of the members 203, 204, 205, 206, 206', and 92, may be pivoted out of operative engagement with the cartons to permit inspection of the work or to clear out the machine in case some of the cartons get jammed. The cartons are moved along by the transporter until they are in a position directly between the opposite glue applying rollers 213 and 213', at which position the flaps 211 and 212 occupy the positions shown in Figs. 34 and 35. These flaps are now ready to receive a coating of glue on the surface adjacent the rollers and this is done in the following manner.

With reference to the glue applying apparatus at the right in Figs. 34 to 36, inclusive, it will

be noted that the roller 213 is journaled in bearings on the opposite edges of the glue trough 214. The roller extends down into the trough 214 an amount sufficient to receive a coating of glue 5 on the surface thereof as the roller is rotated. A gear 215 is mounted on the same shaft as the roller 213 and this gear is rotated by means of the gears 216 and 217 the latter being mounted upon the shaft 219 which carries a sprocket 218 driven by means of a sprocket 199 from a sprocket 10 mounted on the main drive shaft 19. The roller 213 is timed so that it rotates but once to every forward movement of the transporter. In other words, it rotates once each time a carton is moved 15 into the position shown in Fig. 34.

In prior gluing devices, it was not necessary to have the gluing roller rotate in timed relation to the movement of the cartons as the flaps on the carton merely passed over the surface of the rollers and picked up a certain amount of the glue while passing thereover. However, the disadvantage of using such a roller was that the flaps often picked up more glue than was necessary to securely hold the flap in position when 20 folded against the other flaps of the carton. The present device has means for applying just the required amount of glue to the flap, and this means will now be described.

A shaft 222 is rotatably mounted in bearings 25 on the trough 214. A scraper 220 rigidly mounted on the shaft 222 has a pair of spaced arms 221 which lie alongside the flat faces of the roller and in close proximity thereto so as to scrape any glue from the edges of the roller so that this glue 30 will not be thrown against the carton or against the flap but will be returned to the glue trough 214. The edge of the scraper which lies adjacent the peripheral surface of the roller 213 in the manner shown in Fig. 34 is adapted to scrape the glue from said surface while in said position 35 so that ordinarily no glue is supplied by the roller 213 to the position where the flap is to be glued. However, at given intervals, means is provided for permitting a small amount of glue to remain 40 on the peripheral surface of the roller and this is, in turn, carried to the flap at the position where it is to be glued and an abutment 235 forces the flap into engagement with the glue on the roller so that it is removed therefrom and remains on said flap. This small amount of glue 45 which remains on the roller is represented by the numeral 236 in Figs. 34 and 35. The glue 236 is permitted to remain on the surface of the roller by simply raising the scraper 220 for a small 50 interval of time and permitting some of the glue to pass between the scraping edge thereof and the peripheral surface of the roller. To raise the scraper 220, a cam 230 is rigidly mounted on the shaft 219 and this is engaged by a follower 229 which rocks the lever 226 about its pivot when 55 actuated by the cam. This lever 226 is loosely mounted on the shaft 222 and is yieldingly urged clockwise about the shaft 222 by means of the spring 228. This insures that the roller 229 always remains in engagement with the cam 230. A pin 227 on the arm 226 engages a stop 224 integral 60 with the arm 225 rigidly mounted on the shaft 222 and adapted to rotate thereon. In order to clamp the arm 225 in adjusted angular position relative to the shaft 222, this arm is provided with a split bearing surrounding the shaft and a screw 233 is used to tighten the split bearing upon the shaft. The arm 225 is adjusted into the position shown in Fig. 34 so that when the 65 roller 229 is on the high part of the cam, the

pin 227 is in engagement with the stop 224 and the scraper is against the peripheral surface of the roller 213. The stop 224 is normally urged against the pin 227 by means of a spring actuated arm 223 adjustably fastened to the other end 70 of the shaft 222. A spring 234 has its opposite ends mounted in recesses in the arm 223 and in the frame of the glue trough 214 to actuate the arm 223. The force with which the stop 224 is urged against the pin 227 is determined by the 75 angular position in which the arm 223 is adjusted relative to the shaft 222. The arm 223 can be adjusted by loosening the screw 232 and rotating it into the desired position relative to the shaft 222 and again tightening the screw 232 80 to hold the arm in adjusted position.

The operation of this device is as follows:—

The cam 230 is provided with a flat portion 231 and when this flat portion comes into a position adjacent the roller 229, the spring 228 rotates the arm 226 clockwise, thereby moving the pin 227 to the left and permitting the arm 225 and the stop 224 to rotate to the left under the action of the spring 234. The rotation of the arm 225 rotates the shaft 222 and raise the scraper 220 95 from the periphery of the roller, thereby permitting a small amount of glue 100 to remain on the surface of the roller in the manner illustrated in Fig. 35. This small amount of glue is then carried over against the flap 212 which removes 105 the glue from the roller. The carton is then moved into the next position where this flap is folded over the flaps which have already been 110 folded so as to seal the carton. A similar gluing device is used to apply glue to the flap 211 at the other end of the carton and this gluing device is similar to the gluing device just described in detail, the parts 213', 214', 215', 217', 218', 219', 220', 222', 223', 225', 226', 227', 228', 233' and 234' corresponding to the parts 213, 214, 215, 217, 115 218, 219, 220, 222, 223, 225, 226, 227, 228, 233 and 234 of the gluing device described.

The gears 215' and 217', however, are in direct mesh and do not have a gear such as 216 interposed therebetween as in the gluing device shown 120 at the right. This is so as to have the roller 213' move in a direction opposite to the roller 213 so that both rollers are moved downwardly at the position where they will engage the respective flaps 211 and 212. A chain 198 passing 125 over the idlers 196 and 195 is adapted to drive the sprocket 218' from a sprocket located on the drive shaft 19.

It is preferable that the glue rollers be rotated so that each time the scrapers are raised the glue 130 is permitted to remain on different portions of the peripheries thereof. The reason for doing this is to prevent the accumulation of dried glue at one spot on each of the glue rollers. If this were permitted, the dried glue would soon be 135 thick as the clearance between the scrapers and rollers and the scrapers would scrape all of the fresh glue off the layer of dried glue and none of the fresh glue would remain to be applied to the flaps on the cartons. If the glue is permitted 140 to remain on different portions of the peripheries each time, the scrapers will scrape the glue from the peripheries at the places where the glue was previously and therefore no dried glue will be 145 permitted to remain on the peripheries of the rollers. As will be noted in the drawings the gearing is such that the rollers will be rotated between presentation of successive cartons an amount which will accomplish the aforementioned result. The gears 217 and 217' are slight- 150

ly larger than gears 215 and 215' so that one rotation of gear 217 or 217' causes more than one revolution of the gear 215 or 215' as the case may be and the scrapers will therefore remove glue from different sections of the peripheries of their respective rollers on each succeeding revolution of the rollers.

After the glue has been applied to the flaps 211 and 212, the carton is moved to a position between the members 238 in the manner shown in Fig. 36. Each of these members 238 has an opening 242 adapted to receive the flap as the carton is moved into position between said members. Projections 240 hold the remaining flaps in folded position and projections 241 are adapted to engage the flaps 211 and 212 when the members 238 are moved vertically and to press said flaps against the already folded flaps and to thereby seal the ends of the carton. The members 238 are adapted to be moved vertically by cam actuated levers 239 after the flaps 211 and 212 have been received in the openings 242.

After the ends of the cartons have been sealed, the cartons are moved to the position shown at the bottom of Fig. 36 so that the cartons are in engagement with each other. The cartons now can be removed from the runways by hand or by any other means desired or they may be permitted to travel to the end of the supports 76' and drop into a suitable receptacle.

The operation of the device is as follows:—

Circulars are fed from the hopper 29 along the supports 76 and 76' into successive positions. The first of these positions is the position where the carton is opened, the next is where the carton is adapted to be filled, the next several positions are where the flaps are folded with the exception of the two which are to receive the glue, the next position is where the flaps have the glue applied thereto, and the last position is where the glued flaps are folded. Circulars are fed from the hopper B to a position just in front of the carton at the position where it is to be filled. The ejector 119 ejects the articles from the chain 4 into the carton 30 at the position where the carton is to be filled, the circular being carried along therewith in a manner which has been described. The chain moves slowly during the time the ejector is ejecting the articles from the chain and moves rapidly to position successive articles at the position where they are to be ejected. After the carton has been filled, the flaps are folded and glued in the manner which has been described.

Obviously those skilled in the art may make various changes in the details and arrangement of parts without departing from the spirit and scope of the invention as defined by the claims hereto appended, and I therefore do not wish to be restricted to the precise construction herein disclosed.

Having thus fully disclosed an embodiment of my invention, what I claim and desire to secure by Letters Patent of the United States is:—

1. In a carton filling machine, the combination with a carton positioning member, of an article positioning member, means for positioning a circular between a carton and an article which is to be inserted in said carton, means for bending said circular, and means for moving said article against said circular at substantially the place where the circular is bent so that the circular will fold over the article and be carried along therewith as it moves toward and into the carton.

2. A carton filling machine adapted to simultaneously insert a circular and an article into a car-

ton comprising means for positioning said article so that it can enter the carton, means for positioning the circular between the article and carton, and means for bending the circular prior to the time when said circular is engaged by said article.

3. A carton filling machine adapted to simultaneously insert a circular and an article into a carton comprising means for positioning said article so that it can enter the carton, means for positioning the circular between the article and carton, and mechanical means independent of the article for bending the circular prior to the engagement of the article with the circular.

4. In a carton filling machine, the combination with a reciprocating means for successively positioning a plurality of empty cartons at a stationary position where they can receive an article, a continuously moving support for carrying articles past said position, and means for moving an article from said support into a carton located at said position, while said support is in motion.

5. A device as claimed in claim 4 which includes a guiding means for guiding said article as it moves from said support into said carton.

6. A device as claimed in claim 4 including means for positioning a circular between the carton and article so that the circular is carried by said article toward and into said carton.

7. In a carton filling machine, the combination with a continuously moving support adapted to support a plurality of articles, means for positioning empty cartons at a stationary loading position adjacent said continuously moving support, an ejector for moving an article from said support into a carton located at the loading position, and means for causing said ejector to move along with the continuously moving support while said ejector is ejecting an article from said support.

8. In a carton filling machine, the combination with a continuously moving chain, of a plurality of pockets in said chain adapted to receive an article which is to be placed in a carton, a carton support, an ejector for moving articles from said pockets into a carton located on said carton support, and a cam for moving said ejector substantially in unison with the movement of the pocket while said ejector is moving the article from said pocket, said ejector returning to its original position after said article is ejected to eject an article from the next succeeding pocket.

9. In a carton filling machine, the combination with a continuously moving chain having pockets therein, a carton support adjacent said chain, an ejector which moves into the pockets 130 to successively eject articles located therein, means to position cartons on said carton support in a position to receive the ejected articles, and a cam for raising said ejector clear of said pockets as it returns to a position where it 135 can eject the next article from its pocket.

10. A carton filling machine comprising a conveyor, a plurality of pockets in said conveyor adapted to receive articles which are substantially cylindrical in cross section and which have 140 a flat portion at one end thereof of greater width than the width of said pocket, means for turning said article in said pocket when said flat portion straddles the edges of said pocket comprising a kicker which moves upwardly to raise 145 one edge of said flat portion and permits the other edge thereof to drop into the pocket along with the rest of the article.

11. A device as claimed in claim 10 in which a means is provided for turning said article after 150

it has been completely received within said pocket, comprising a pivoted plate for engaging said flat portion of said article as it is carried past said plate.

5 12. In a carton filling machine, the combination with a movable work support, of a carton support, means for positioning a carton on said carton support so that it is in a position to receive an article in said article support, means 10 for moving an article from said support into said carton, means for positioning a circular between said carton and said article, and means for bending the circular, said means for bending the circular being actuated by the article as it moves 15 thereagainst.

13. In a carton filling machine, the combination with a continuously moving chain, a plurality of article receiving pockets therein, a carton support, means for positioning a carton in 20 a position to receive articles supported in said pockets, an ejector for moving an article from one of said pockets into said carton, means for positioning a circular between said article and said carton, and means movable with said ejector 25 adapted to bend said circular prior to the time when said circular is engaged by the article for folding the circular so that it will be folded over the article and be carried along therewith into the carton.

30 14. A device as claimed in claim 13 in which means is provided for returning the circular folding means to its original position.

15. In a carton filling machine, the combination with a movable article support, means for 35 supporting a carton adjacent said article support, an ejector for moving an article from said article support into a carton located on said carton support, means for positioning a circular between said article and said carton before the 40 article is ejected from the support, a folding device for folding the circular, said circular being movable into said carton simultaneously with said article and means for positively returning said folding device into its original position.

45 16. A device as claimed in claim 15 in which the folding device is returned to its original position by means of a friction device having operative engagement therewith.

17. In a carton filling machine, means for 50 positioning an article and a carton opposite each other with a circular therebetween, a folding device for partially folding said circular, an ejector for moving the article against the circular so that said circular is carried along with said article 55 into said carton, a lever pivoted to said folding device and movable with said ejector during a portion of its forward movement, and means connected with said ejector for causing said lever to move therewith on its return movement so 60 that the folding device is returned to its original position.

18. A carton filling machine comprising a hopper in which cartons are adapted to be stacked 65 while in unopened position, an opening at one side of said hopper through which the cartons are moved one by one, means for engaging but one of said cartons in the hopper and for moving said carton through said opening, a gate adjustably mounted so that it can vary the effective width of said opening to insure that only 70 one carton will be carried therethrough, and means for agitating said gate at a predetermined time to cause said gate to move the cartons in 75 said hopper toward a position where one of the

cartons can be engaged by the means adapted to move the carton through said opening.

19. A carton filling machine comprising a hopper adapted to receive a stack of cartons, a member for engaging a carton at one end of said stack for moving said carton out of the hopper, a cam for positioning said member so that it will engage said carton, and a second cam for preventing said member from moving away from said carton as the carton is being moved from the hopper. 80

20. A device as claimed in claim 19 in which the first-mentioned cam is operative only during the beginning of the movements of said member. 90

21. In a carton filling machine, the combination with a continuously moving feed chain, of a means for feeding cartons into a position adjacent said feed chain, an ejector for successively moving each article located in said feed chain to a position within one of said cartons, means for positioning a circular between each article and the carton into which it is to be moved so that as the article is moved into the carton it will engage the circular and carry it into the 100 carton simultaneously with the movement of the article into the carton. 95

22. A device as claimed in claim 21 in which the ejector for moving the articles from the chain is adapted to move along with the chain 105 in the direction of its movement during the time that said ejector is moving an article from said chain.

23. A device as claimed in claim 21 in which the chain moves at alternately fast and slow 110 speeds.

24. In a carton filling machine, the combination with a continuously moving feed chain for supporting articles to be placed in cartons, of a means for feeding cartons to a position in 115 which they may receive an article from said feed chain, an ejector for moving an article from said feed chain into a carton located at said position, a cam for raising said ejector clear of said feed chain as it moves back into a position where it can move the next article from said feed chain, and means for inserting a circular into said carton simultaneously with the movement of the article thereinto comprising a breaker for folding said circular so that said circular will fold over said article and be carried along thereby as said article moves into 120 said carton. 125

25. A device as claimed in claim 24 in which means is provided for folding the flaps of said 130 carton after the article has been inserted in said carton, and means for applying glue to one of said flaps prior to the time when that flap is folded.

26. In a machine of the class described, the combination with an article conveyor, of means for continuously actuating said conveyor at a varying speed past a carton receiving position, and means for ejecting said articles from said conveyor into a carton at said position while 135 said conveyor is moving relative to said carton. 140

27. In an article cartoning machine, the combination with a conveyor for articles, of a conveyor for cartons, means for moving one of said conveyors at a continuous but varying speed and relatively to said carton, and means for moving said articles into cartons when said articles and cartons are substantially adjacent to but moving relative to each other. 145

28. A carton filling machine adapted to insert 150 an article and a circular in a carton, comprising

- means for positioning an article adjacent an open end of a carton, means for positioning a circular between said carton and article, and means for moving said article against said circular and into said carton. 5 to drop into the pocket at the proper angle thereto.
29. In a carton filling machine, the combination with means for successively positioning a plurality of cartons in a position where they can receive an article, a continuously moving support for carrying articles past said position, means for moving an article from said support into a carton located at said position, and means for positioning a circular between said carton and article so that the circular is carried by 10 said article toward and into said carton. 80
30. In a carton filling machine, the combination with a continuously moving support adapted to support a plurality of articles, of means for positioning empty cartons at a loading position, 15 and an ejector for ejecting successive articles from said support into said cartons, said ejector moving with said support while said article is being ejected but returning to a position to eject the next successive article from said support after ejecting said first mentioned article. 85
31. In a carton filling machine, the combination with a continuously moving support adapted to support a plurality of articles, of means for successively positioning empty cartons at a loading position, and a single ejector for ejecting a plurality of articles successively into successive cartons located at said position when each of said articles arrives at a position substantially opposite the open end of said carton. 90
32. In a carton filling machine, the combination with a continuously moving support adapted to support a plurality of articles, of means for successively positioning empty cartons at a loading position, and a single ejector for ejecting a plurality of articles successively into successive cartons located at said position when each of said articles arrives at a position substantially opposite the open end of said carton, said ejector also moving in the direction of travel of said support as an article is being ejected from said support and then returning to its original position to be in readiness to eject the next successive article into a carton located at said position. 100
33. A device of the class described comprising a conveyor having a plurality of pockets therein, means for moving said conveyor along a predetermined path, and a movably mounted weighted member adapted to engage articles in 105 said pocket and turn said articles in said pockets to a predetermined position, said articles having projecting portions thereon the amount of turning of said article being limited by the projecting portion of said article engaging a wall of said pocket. 110
34. A carton filling machine comprising a moving conveyor having a plurality of open-sided rectangular pockets therein adapted to receive an article having a portion the section of which is of greater length than said open-side but the width and which is not, of means for turning said article so that said article occupies a position in which the longest dimension of said section lies substantially parallel to the diagonal of said rectangular pocket comprising an arm operable at one position of said pocket adapted to engage one end of said elongated section and raise the same away from the open side of said pocket to 115 permit the opposite side of said elongated section to drop into the pocket at the proper angle thereto. 120
35. A device as claimed in claim 34 in which means is provided for turning said article after the same is completely received in said pocket, comprising a plate yieldingly mounted and adapted to engage one end of said elongated portion as said conveyor moves relatively to said plate. 125
36. A carton filling machine comprising a support for an open-mouthed carton, a support for an article to be inserted in said carton, means for alining said article in front of the open-mouth of said carton, and mechanism for feeding a circular with a step by step movement to a position between said article and carton. 130
37. In a carton feeding mechanism, the combination with a carton hopper, spaced ledges upon which the end carton of a stack of cartons in said hopper is adapted to rest, a stripper member having a surface for engaging the underside of said carton, and a surface for engaging the edge thereof, said latter surface projecting above said former surface an amount sufficient to engage only the number of cartons desired to be removed from said hopper, means for moving said latter surface towards the edges of said cartons to strip the desired number from the bottom thereof, and means for permitting said stripper to yield towards and from said stack to either side of the position which said stripper occupies at the time it engages the number of cartons to be stripped, after the stripper commences its stripping movement. 135
38. In a carton feeding mechanism, the combination with a carton hopper, spaced ledges upon which opposite edges of the lowermost one of a stack of cartons are adapted to rest, the intermediate portion of said carton being unsupported, a stripper movable transversely to said hopper for stripping the lowermost one of said cartons from 140 said stack, a member yieldingly mounted thereon, an abutment projecting therefrom adapted to engage the edge of only one carton, said member permitting said abutment to follow the contour of the surface of the next succeeding carton in said stack after said carton to be stripped is engaged by said abutment to insure that the carton being removed does not come out of engagement with said abutment, said abutment having permitted upward movement after engagement with the carton to be stripped so that the same will follow the contour of the next adjacent carton to the one being stripped during the stripping of the carton from the stack. 145
39. A device as set forth in claim 38 in which the stripper carries transport means for moving said cartons to successive positions after said carton leaves said hopper. 150
40. In a stripper for stripping a carton from the end of a stack of cartons, comprising a member movable transversely to said stack, a second member having an abutment for engaging an edge of said end carton, yieldingly mounted on said first member so as to move toward said stack, and means for preventing said stripper from moving away from said stack comprising a rigid abutment which is operative during substantially the entire stripping of said carton from said stack. 155
41. In a carton feeding mechanism, the combination with a hopper, of a transport bar, means on said transport bar for feeding cartons in flat folded condition from said hopper, means for preventing movement of said cartons bodily away from said transport bar after they are removed from said hopper but permitting unfolding of said 160

cartons, and means carried entirely by said transport bar for unfolding said cartons and squaring them into proper shape.

42. In a carton feeding mechanism, the combination with a hopper, of a transport bar, means on said transport bar for feeding cartons in flat folded condition from said hopper, means for preventing movement of said cartons bodily away from said transport bar after they are removed from said hopper but permitting unfolding of said cartons, and means carried entirely by said transport bar for unfolding said cartons and squaring them into proper shape, said last mentioned means comprising spaced projections on said transport bar for engaging said cartons and for abutting against opposite sides of said cartons when opened.

43. In a carton feeding mechanism, the combination with a hopper, of a transport bar, means on said transport bar for feeding cartons in flat folded condition from said hopper, means for preventing movement of said cartons bodily away from said transport bar after they are removed from said hopper but permitting unfolding of said cartons, and means carried entirely by said transport bar for unfolding said cartons and squaring them into proper shape, said last mentioned means comprising spaced projections on said transport bar for engaging said cartons and for abutting against opposite sides of said cartons when opened, one of said projections also acting as a means for feeding said cartons to a position where the same are to be filled.

44. In a carton feeding mechanism, the combination with a transport member adapted to move cartons to successive positions, of a second member adapted to enter flat folded cartons, and means carried entirely by said transport member adapted to engage opposite sides of said carton and fully open the same while said second member prevents movement of said carton away from said transport member.

45. In a circular feeding mechanism for machines of the class described, the combination of spaced substantially parallel guides, means for feeding a circular transversely to said guides adjacent one end thereof, means for engaging an intermediate portion of said circular and for moving said intermediate portion between said guides in advance of the remaining portions to thereby fold said circular about said means, a second means for retracting said first means, means for preventing retrograde movement of said folded circular, and mechanism movable with said first means for advancing said circular with a step by step movement through the space between said guides, said circulars being prevented from retrograde movement at each step during their movement between said guides.

46. In a carton feeding mechanism, the combination of a carton hopper, of a movable gate at the side of the hopper from which the cartons are to be removed and in engagement with the cartons in said hopper, a movable stripping member for removing cartons from said hopper, an opening member movable transversely to said stripper for entering the cartons after said cartons leave the hopper, said gate permitting only one carton to be removed from said hopper while said gate is in one position, means movable with said opening member to move said gate to another position after each carton is removed from said hopper, and means for returning said gate to its original position to thereby cause said gate

to move the cartons in said hopper towards said stripping member.

47. In a carton feeding mechanism, the combination of a carton hopper, of a movable gate at the side of the hopper from which the cartons are to be removed and in engagement with the cartons in said hopper, a movable stripping member for removing cartons from said hopper, an opening member movable transversely to said stripper for entering the cartons after said cartons leave the hopper, said gate permitting only one carton to be removed from said hopper while said gate is in one position, means movable with said opening member to move said gate to another position after each carton is removed from said hopper, and yielding means for returning said gate to its original position to thereby cause said gate to move the cartons in said hopper towards said stripping member.

48. In a cartoning machine, of mechanism for supporting an open-ended carton and an article with said article opposite the open end of said carton, of means for feeding a circular between said carton and article, a member having an opening therein and arranged between said circular and said carton, means for moving said article forwardly through said opening, and a breaker member in advance of said article for engaging a portion of said circular and for forcing said circular partially through said opening, the edges of said opening and said breaker co-operating to fold said circular intermediate its ends, said article moving against said fold and continuing the movement of said circular through said opening and into said carton.

49. In a cartoning machine, of mechanism for supporting an open-ended carton and an article with said article opposite the open end of said carton, of means for feeding a circular between said carton and article, a member having an opening therein and arranged between said circular and said carton, means for moving said article forwardly through said opening, and a breaker member in advance of said article for engaging a portion of said circular and for forcing said circular partially through said opening, the edges of said opening and said breaker co-operating to fold said circular intermediate its ends, said article moving against said fold and continuing the movement of said circular through said opening and into said carton, said breaker being pivoted and actuated by said article in the manner set forth.

50. In a cartoning machine, of mechanism for supporting an open-ended carton and an article with said article opposite the open end of said carton, of means for feeding a circular between said carton and article, a member having an opening therein and arranged between said circular and said carton, means for moving said article forwardly through said opening, and a breaker member in advance of said article for engaging a portion of said circular and for forcing said circular partially through said opening, the edges of said opening and said breaker co-operating to fold said circular intermediate its ends, said article moving against said fold and continuing the movement of said circular through said opening and into said carton, said breaker being frictionally connected to said article moving means so as to move therewith to thereby fold said circular independently of said article.

51. A device as claimed in claim 50 in which the forward movement of said breaker is arrested before the completed forward movement of said ar-

- ticle is accomplished, thereby causing said breaker to slide relatively to said article moving means due to the frictional contact therewith, and in which means is provided for restoring the breaker and article moving means to their original operative positions relatively to each other on the return movement of said article moving means. 52. In a carton filling machine, the combination with a continuously moving conveyor having a plurality of article pockets, of means for positioning cartons opposite articles located at a carton filling position, a single ejector movable transversely to the movement of said conveyor for successively ejecting all articles arriving at said position from each of said pockets as said article arrives adjacent said position, and means for moving said ejector in the direction in which said conveyor moves while an article is being ejected from a pocket and for thereafter returning the same to a position to eject the next article in the same manner. 53. In a carton filling machine, the combination with a continuously moving conveyor having a plurality of article pockets, of means for positioning cartons opposite articles located at one position, a single ejector movable transversely to the movement of said conveyor for ejecting articles from each of said pockets as it arrives adjacent said position, means for moving said ejector in the direction in which said conveyor moves while an article is being ejected from a pocket, means for returning said ejector to its original position after it has ejected an article from a pocket, and means for raising said ejector clear of the walls of said pockets on its return movement so that it clears said conveyor. 54. In a cartoning machine, the combination with a continuously movable article holding member, of a carton support, an ejector for moving articles from said article holding member into a carton on a support, means for moving said ejector in the direction of movement of said article holding member while said article is moving into said container, a bar frictionally held against said ejector, a folding member attached to said bar, a stop for limiting the movement of said folding member before said ejector moves the full extent of its travel in one direction, and a second stop operable on the reverse movement of said folding member for returning said bar to its original position relative to said ejector. 55. In a cartoning machine, the combination with a conveyor having article receiving pockets therein, means for moving said conveyor at alternately slow and fast speeds, an ejector for ejecting articles out of said pockets when said conveyor is moving slowly, and means for positioning a carton at a fixed position to receive an article being ejected from said pocket as it moves past said fixed position. 56. In a cartoning machine, the combination with a conveyor having article receiving pockets therein, means for moving said conveyor continuously but alternately at relatively slow and fast speeds, an ejector for ejecting articles from said pockets at a given position, a hopper for cartons, a stripping member for stripping cartons from said hopper and moving them with a step by step movement towards said position, said stripping member having means thereon for engaging opposite sides of a folded carton to cause said carton to unfold, means adapted to be positioned within said carton while said last mentioned means is unfolding said carton, means for thereafter holding said carton open, means for presenting a circular between a carton located at said position and an article which is to be inserted therein, a folding device adapted to fold said circular prior to moving said article into said carton, said article being adapted to engage said circular and carry the same into said carton therewith, means for closing the ends of said carton, and means for applying glue to one portion of each folded end so that when said ends are folded the same will be retained in place by said glue. 57. A feed chain having pockets for the reception of articles to be packaged, means for supplying cartons to a loading position, and a variable speed device for imparting continuous movement of said chain relative to said position comprising driving and driven rotatable members having their axes off-set from each other, a pin and slot connection operatively connecting said rotatable members to actuate said driven member at a variable speed, operative driving connections from said driven member to said feed chain for actuating the same, and means for ejecting articles from the pockets of said chain into a carton located at said position and while said chain is in motion. 58. In a device of the class described, the combination with a work support, of a driven member operatively connected to said work support, a driving member having loose connection with said driven member so as to impart a variable speed to said driven member when said driving member is rotated at a constant speed, and means for ejecting articles from said work support into a stationary carton while said work support is in motion. 59. In a carton filling machine, the combination with a hopper for a stack of cartons of means within said hopper for always positioning one of the edges of the end-most carton in the same position relative to the hopper regardless of whether the carton is flat or warped in either direction from normal, and stripping mechanism for engaging the edge of the end-most carton for stripping said carton, said stripping mechanism having permitted movement toward and away from said stack of articles after it engages said stack of articles between the position which said stripping mechanism has when the same engages said cartons and the carton next adjacent that being removed so that the same can move toward or away from said stack of articles and remain in engagement with the carton being stripped throughout the entire stripping operation, the position at which said stripping mechanism engages said carton being the limiting position to which the same may be moved away from said cartons during the stripping operation. 60. A carton filling machine comprising a continuously moving support for articles, means for positioning cartons at a fixed position and substantially in alignment with articles on said support when said support is at a predetermined position in its movement, and means for moving the articles from the support into the cartons as said support moves relative to said position. 61. In a stripper, for stripping a carton from the end of a stack of cartons, comprising a member movable transversely to said stack, a second member having an abutment for engaging the edge of said end carton and yieldingly mounted on said first member so as to move toward said stack a substantial amount, and means for restraining said member from moving all of its permitted movement toward said stack until said second member begins to move a carton

from said stack, said last mentioned means being rendered inoperative after the carton begins its movement under the action of said second member.

5 62. In a stripper for stripping a carton from the end of a stack of cartons, comprising a member movable transversely to said stack, and a second member having an abutment for engaging an edge of said end carton and yieldingly mounted on said first member so as to move toward said stack, and means for positively preventing movement of said second member away from said stack more than its initial position when engaging said carton being stripped and while 10 said second member is moving the end-most carton of said stack to its next succeeding position.

63. In a carton feeding mechanism, the combination with an open-ended hopper, of a member movable across the open end of said hopper, 20 a bar pivoted to said member, a projection on said bar extending above the surface of said bar substantially the thickness of a carton to be removed from said hopper, the surface of said bar which is adjacent said projection and which 25 extends away therefrom in a direction toward the cartons in the hopper, sloping downwardly and away from said projection, a spring for urging said bar about its pivot towards the end one of a stack of cartons in said hopper, mechanism for 30 moving said member bodily toward and away from the end of said hopper and also transversely thereto along a closed circuitous path such that said member periodically returns to carton stripping position, and an abutment for preventing 35 movement of said bar away from said stack of cartons while said projection is stripping a carton from said stack, said path being such as to carry said member out of engagement with the cartons in said hopper except during the carton 40 stripping movement thereof.

64. In a cartoning machine, the combination with means for positioning successive cartons at a loading position, of a continuously moving conveyor for moving articles past said loading position to bring each of the articles on said conveyor adjacent said loading position, a single ejector for ejecting successive articles from the conveyor into successive cartons located at said position, and means for moving said ejector in 45 the direction of conveyor travel while the article is being ejected into a carton at the loading position and for thereafter returning said ejector to a position to engage the next article and move the same into the next carton located at said 50 position.

65. In a packaging machine for enclosing articles within cartons, the combination with a conveyor having a plurality of article receiving pockets, means for continuously moving said conveyor to present articles located in said positions to a loading position, means for positioning cartons adjacent said loading position to receive articles from said article receiving position on said conveyor while said articles are adjacent said loading position, an ejector mounted for movement transversely to the movement of said conveyor to move said articles off said conveyor into said cartons while said conveyor is moving and when the articles to be ejected arrive adjacent 60 said loading position, said ejector being also mounted for movement substantially in unison with said conveyor during the ejecting of the articles therefrom, means for moving said ejector in the direction of conveyor movement while the article is being moved off said conveyor by said ejector, means for immediately returning said ejector thereafter to its initial position so that the next article presented at 65 said loading position for enclosure in a carton at said loading position may be ejected from said conveyor by said ejector, and means for raising said ejector clear of said conveyor and the articles thereon during the return movement of said ejector to its initial position.

66. In a packaging machine for enclosing articles within cartons, the combination with a conveyor having a plurality of article receiving pockets therein, means for continuously moving said conveyor along a predetermined path to present articles in said pockets at a loading position, means for positioning cartons adjacent said loading position to receive articles from said pockets when said pockets are at said loading position,

ejector, and means for immediately returning said ejector thereafter to its initial position so that the next article presented at said loading position for enclosure in a carton at said loading position may be ejected from said conveyor by said ejector.

67. In a packaging machine for enclosing articles within cartons, the combination with a conveyor having a plurality of article receiving pockets, means for continuously moving said conveyor to present articles located in said positions to a loading position, means for positioning cartons adjacent said loading position to receive articles from said article receiving position on said conveyor while said articles are adjacent said loading position, an ejector mounted for movement transversely to the movement of said conveyor to move said articles off said conveyor into said cartons while said conveyor is moving and when the articles to be ejected arrive adjacent said loading position, said ejector being also mounted for movement substantially in unison with said conveyor during the ejecting of the articles therefrom, means for moving said ejector in the direction of conveyor movement while the article is being moved off said conveyor by said ejector, means for immediately returning said ejector thereafter to its initial position so that the next article presented at said loading position for enclosure in a carton at said loading position may be ejected from said conveyor by said ejector, and means for thereafter moving said ejector in a direction opposite to its ejecting movement and also in a direction opposite to its movement with said conveyor to reposition said ejector at its initial position for ejecting a succeeding article from said conveyor.

68. In a packaging machine for enclosing articles within cartons, the combination with a conveyor having a plurality of article receiving pockets, means for continuously moving said conveyor to present articles located in said positions to a loading position, means for positioning cartons adjacent said loading position to receive articles from said article receiving position on said conveyor while said articles are adjacent said loading position, an ejector mounted for movement transversely to the movement of said conveyor to move said articles off said conveyor into said cartons while said conveyor is moving and when the articles to be ejected arrive adjacent said loading position, said ejector being also mounted for movement substantially in unison with said conveyor during the ejecting of the articles therefrom, means for moving said ejector in the direction of conveyor movement while the article is being moved off said conveyor by said ejector, means for immediately returning said ejector thereafter to its initial position so that the next article presented at said loading position for enclosure in a carton at said loading position may be ejected from said conveyor by said ejector, and means for raising said ejector clear of said conveyor and the articles thereon during the return movement of said ejector to its initial position.

69. In a packaging machine for enclosing articles within cartons, the combination with a conveyor having a plurality of article receiving pockets therein, means for continuously moving said conveyor along a predetermined path to present articles in said pockets at a loading position, means for positioning cartons adjacent said loading position to receive articles from said pockets when said pockets are at said loading position,

- an ejector having a head thereon of substantially the same width as the pockets and mounted for movement transversely to the movement of said conveyor for ejecting articles from said 5 pockets, means for moving said ejector transversely to the movement of said conveyor to cause the head of said ejector to move into and through said pocket to eject an article therefrom into a carton at said loading position, and means for 10 moving said ejector head in unison with said conveyor during the movement of said ejector head through said pocket during ejecting movement, and means for thereafter immediately returning said ejector to its initial position to eject a succeeding 15 article arriving at said loading position into a carton at said position. 69. In a packaging machine for enclosing articles within cartons, the combination with a conveyor having a plurality of article receiving 20 pockets therein, means for continuously moving said conveyor along a predetermined path to present articles in said pockets at a loading position, means for positioning cartons adjacent said loading position to receive articles from said pockets when said pockets are at said loading position, an ejector having a head thereon of substantially the same width as the pockets and mounted for movement transversely to the movement of said conveyor for ejecting articles from said pockets, 25 means for moving said ejector transversely to the movement of said conveyor to cause the head of said ejector to move into and through said pocket to eject an article therefrom into a carton at said loading position, means for moving 30 said ejector head in unison with said conveyor during the movement of said ejector head through said pocket during ejecting movement, means for thereafter immediately returning said ejector to its initial position to eject a succeeding article 35 arriving at said loading position into a carton at said position, and means for raising the head of said ejector clear of said pocket during the return movement of said ejector to its initial 40 position. 70. A carton filling machine comprising a conveyor having a plurality of pockets therein adapt- 45
- ed to receive articles having one transverse dimension greater than the width of the mouth of said pocket so that as said articles are positioned in said pockets, some of said articles may be prevented from moving all of the way into said pocket due to that portion of said article having said greater dimension straddling said pocket, and a kicker movable transversely to said conveyor movement for engaging one edge of any such article so improperly positioned to lift the same away from the pocket a sufficient amount to permit the opposite edge thereof to fall into said pocket, whereafter said kicker moves to inoperative position and said article falls into said pocket the desired amount. 80
71. In a cartoning machine, the combination with a conveyor having a plurality of pockets therein moving in a predetermined direction along a predetermined path, of a member adapted to overlie said conveyor and extend into close proximity with the upper side thereof, and yielding means for urging said member toward said conveyor in a direction opposite to the movement of said conveyor, said pockets being adapted to receive articles having a projecting portion thereon, which projecting portion is adapted to lie in a certain position with respect to said pocket, said pocket being of substantially the same width as the articles to be received therein, not including said projecting portions thereon, and said member lying in the path of movement of said projecting portions if the said projecting portions occupy an improper position with respect to said pockets as said articles move to a position adjacent said member, whereby said member will engage said projecting portions and turn said articles to a position wherein said projecting portions occupy their proper positions with respect to their respective pockets, one wall of each of said pockets preventing the respective article in that pocket from moving bodily relative to said conveyor in the direction of the movement of said conveyor or in the opposite direction during the turning movement of said articles within said pockets. 90
